UNITED STATES PATENT OFFICE.

STANLEY S. MIZNER, OF STURGIS, MICHIGAN.

APPLICATOR.

Application filed April 17, 1922, Serial No. 553,607.

To all whom it may concern:

Be it known that I, STANLEY S. MIZNER, a citizen of the United States, residing at Sturgis, county of St. Joseph, State of Michigan, have invented certain new and useful Improvements in Applicators, of which the following is a specification.

This invention relates to improvements in applicators. The main objects of this invention are:

First, to provide an applicator which can be conveniently manipulated to apply the medicament at the desired point, as in the nose, throat or ear, or other cavity.

Second, to provide an applicator in which the applicator tube or barrel and rod or plunger are mounted on a handle or stock, so that they may be quickly detached and others substituted, either of the same or different size.

Third, to provide an applicator having a finger actuated lever for controlling the applicator rod or plunger, and of such form as to facilitate use without obstructing vision.

Fourth, to provide an applicator having an adjustable connection between the actuating lever and plunger so that the amount which the medicament carrier is projected may be regulated.

Further objects and objects relating to structural details will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Fig. I is a detail side elevation of my improved applicator, the forward end of the applicator tube or barrel being shown in longitudinal section.

Fig. II is a detail side elevation, similar to Fig. I, with the applicator plunger in projected position.

Fig. III is a detail elevation similar to Fig. I, with portion in section, the main frame being in vertical section on line 3—3 of Fig. IV and the slide member being in section on the slightly different plane of line 3—3 of Fig. V to show structural details and the extended position being shown by dotted lines.

Fig. IV is an enlarged detail transverse section on a line corresponding to line 4—4 of Fig. III showing the attaching nut by which the shank of the applicator tube is 60 detachably clamped in place.

Fig. V is an enlarged detail transverse sectional view taken on line 5—5 of Fig. III showing the details for clamping the applicator plunger to the slide member. 65

Fig. VI is a detail elevation view of the shank of the applicator tube clamped in position on the frame.

In the drawings similar reference characters refer to similar parts throughout the 70 several views, and the sectional views are taken looking in the direction of the little arrows at the ends of the section lines.

Referring to the drawings, the reference character 1 indicates generally the stock or handle frame member, which is provided with finger holds 2 and 3 positioned so that the stock may be grasped between the thumb and forefinger. 75

The stock is provided with an upwardly projecting seat 4 for the shank of the applicator tube 5. The applicator tube 5 is open at its rear end to receive a plunger rod 7 which, in practice, may be a piece of wire adapted by roughening or otherwise to receive the medicament carrier 8 which may be a piece of absorbent cotton twisted upon the rough end of the plunger. 80 85

The barrel 5 is opened laterally at 13 at its forward end deflecting the medicament carrier 8 as desired. The same can, of course, be opened on any side and for certain uses a simple straight tube is all that is required, the straight tube being very effective for the treatment of the back of the throat. However, for substantially all uses the tube open at the side is preferred. 90 95

The plunger is actuated by means of the slide 18 and trigger-like lever 15 pivoted on pivot screw 16 on the stock 1. Lever 15 is slotted at 15' and engages the cross-pin 18' of the actuating slide 18. The slide 18 is mounted upon the rod 19 to reciprocate in a plane parallel with the barrel. The slide has an upwardly and laterally projecting arm 20 provided with a hooked seat 21 to receive the plunger 7. The plunger 7 is adjustably secured to the slide by means of the set screw 22. A spring 23 returns the slide 18 to its initial position. 100 105 110

With the parts thus arranged, the stock may be grasped between the thumb and fore-

finger and the lever actuated like a trigger. The structure is very convenient and practical for use in many relations. It being slightly offset enables the user to sight under or over the barrel and see exactly what he is doing. This instrument may be introduced through a speculum for treatment of the nose, throat, ear or other cavity or opening. It insures the correct application of the medicine or acid used in treating the spot intended and no other than the diseased part.

Having thus described my invention, what I claim as new and desire to secure by Letters Patent, is:

15 1. In an applicator, the combination of a stock having a barrel support at its front end and provided with finger holds permitting the grasping between the thumb and forefinger, a barrel disposed on said support 20 and provided with a slotted flat shank lapping the side of said support, a clamping screw disposed to engage said slotted shank whereby said barrel is detachably secured, a removable plunger, a plunger slide having 25 a seat thereon on which said plunger is disposed and provided with a set screw for adjustably securing the plunger thereto, a guide rod for said slide, a return spring for said slide, and a trigger-like actuating lever 30 pivoted on said stock to engage said slide.

2. In an applicator, the combination of a stock provided with finger holds permitting the grasping between the thumb and forefinger, a barrel mounted on said stock, a removable plunger, a plunger slide having a 35 seat thereon on which said plunger is disposed and provided with a set screw for adjustably securing the plunger thereto, a guide rod for said slide, a return spring for 40 said slide, and a trigger-like actuating lever pivoted on said stock to engage said slide.

3. In an applicator, the combination of a stock having a barrel support at its front end and provided with finger holds permitting the grasping between the thumb and forefinger, a barrel disposed on said seat and provided with a slotted flat shank lapping the side of said stock, a clamping screw disposed to engage said slotted shank whereby 45 said barrel is detachably secured, a plunger, a plunger slide, a guide rod for said slide, a return spring for said slide, and a trigger-like actuating lever pivoted on said stock to engage said slide.

50 4. In an applicator, the combination of a stock provided with finger holds permitting the grasping between the thumb and forefinger, a barrel mounted on said stock, a plunger, a medicine carrier on said plunger, a plunger slide, a guide rod for said slide, a return spring for 55 said slide, and a trigger-like actuating lever pivoted on said stock to engage said slide.

60 5. In an applicator, the combination of a stock provided with finger holds per-

mitting the grasping between the thumb and forefinger, a barrel, a plunger rod projecting from the rear end of the barrel, a medicine carrier on said plunger, a plunger slide having a seat on which said plunger is disposed and provided with a set screw for adjustably securing the plunger thereto, a guide for said slide, a return spring for said slide, and a trigger-like actuating lever pivoted on said stock to engage said slide.

6. In an applicator, the combination of a stock, a barrel, a plunger projecting from the rear end of the barrel, a medicine carrier on said plunger, a plunger slide to which said plunger is adjustably secured, a 80 guide for said slide, a return spring for said slide, and an actuating lever pivoted on said stock to engage said slide.

7. In an applicator, the combination of a stock having a barrel support at its front end, a barrel disposed on said support and provided with a slotted flat shank lapped against the side of the stock, a clamping screw coacting with said slot whereby the barrel is detachably secured to the stock, a 90 plunger projecting from the rear end of the barrel, a medicine carrier on said plunger, and means for actuating said plunger.

8. In an applicator, the combination of a stock having a barrel support at its front end, a barrel disposed on said support and provided with a slotted flat shank lapped against the side of the stock, a clamping screw coacting with said slot whereby the barrel is detachably secured to the stock, a 95 plunger and a medicine carrier on said plunger.

9. In an applicator, the combination of a stock and barrel, an applicator plunger slideable in said barrel with its rear end projecting therefrom and removable to permit the securing of a medicament carrier thereto, a medicine carrier on said plunger, and means for reciprocating said plunger to apply medicament and withdraw the medicament carrier into the barrel comprising a lever adjustably connected to said plunger.

10. In an applicator, the combination of a stock and barrel, an applicator plunger slideable in said barrel with its rear end projecting therefrom and removable to permit the securing of a medicament carrier thereto, a medicine carrier on said plunger, and means for reciprocating said plunger to apply medicament and withdraw the medicine carrier into the barrel.

11. In a structure of the class described, the combination of an applicator barrel mounted so that the rear end is unobstructed, an applicator plunger projecting from the rear end of said barrel and removable therefrom, the front end of said barrel being open to permit the projecting of the medicament carrier, a medicine carrier on said plunger, and means for reciprocating

said plunger to apply medicament and withdraw the medicine carrier into the barrel.

12. In an applicator, the combination of a barrel with a lateral opening at its forward end, and an applicator plunger slideable therein with flexible medicament carrier secured thereto and adapted to be re-

ciprocated in said barrel and applied and withdrawn by said plunger to apply medicament and withdraw the medicine carrier 10 into the barrel.

In witness whereof, I have hereunto set my hand and seal.

STANLEY S. MIZNER. [L.S.]
